This technical drawing illustrates a complex mechanical assembly, possibly a gear or pulley system. The drawing is a cross-sectional view showing internal components and their relative positions. Various parts are labeled with numbers, including:

- 13, 25 (top right)
- 16 (right side)
- 14 (far right)
- 29, 27, 28, 26 (right side)
- 17 (right side)
- 47 (bottom right)
- 49', 46, 48', 45, 48 (left side)
- 19 (bottom left)
- 30, 20, 51, 53, 52, 55, 23, 54, 21, 24 (top and center)
- 18 (top left)
- 47 (bottom center)
- 58, 57 (bottom center)
- 20, 21, 56 (bottom center)

COTTON PICKER

Arthur J. Kay, Los Angeles, Calif.

Application November 28, 1944, Serial No. 565,544

3 Claims. (Cl. 19—80)

1

This invention relates to a cotton picker.

The general object of the invention is to provide an improved apparatus for picking or working over cotton or other material which has become compacted in mattresses.

A more specific object of the invention is to provide a cotton picker including a novel housing.

A further object of the invention is to provide a cotton picker including a novel rotary tooth member.

A further object of the invention is to provide a cotton picker including a novel screen arrangement for removing dirt and other material from the cotton.

Other objects and the advantages of my invention will be apparent from the following description taken in connection with the accompanying drawings, wherein:

Fig. 1 is a side elevation of a cotton picker embodying the features of my invention;

Fig. 2 is a view taken on line 2—2, Fig. 1, with the housing cover removed;

Fig. 3 is an enlarged section taken on line 3—3, Fig. 2;

Fig. 4 is a fragmentary, enlarged plan view showing the screen member and looking in the direction of the arrows 4—4, Fig. 3, and

Fig. 5 is a fragmentary section taken on line 5—5, Fig. 3.

Referring to the drawings by reference characters, I have shown my invention as embodied in a cotton picker which is indicated generally at 10.

As shown the apparatus is mounted on legs 11 which are supported on a base 12. The legs at their tops support longitudinal frame members 13 and transverse frame members 14. The legs also support a shelf 15 on which I arrange an electric motor 16 which drives a belt 17.

Mounted upon the members 13 and 14 I arrange support members 18 and 19. These members 18 and 19 include parallel side portions 20 on which flanges 21 on a housing 22 are arranged. The housing 22 includes a semi-cylindrical intermediate well portion 23 which at each end communicates with a frusto-conical portion 24 and the frusto-conical portion at each end communicates with a further frusto-conical portion 25. The latter are provided with openings 26 through which a shaft 27 extends. The shaft 27 is mounted in bearings 28 and is adapted to be driven by a pulley 29 from the belt 17. The frusto-conical ends cause the cotton being picked to work towards the intermediate well portion so

2

that it will be engaged by toothed members, to be later described.

In line with the well 23 the housing includes a discharge chute 30 which has an outlet 31. Below the chute 30 I arrange a dust chamber 32 which has a lower wall 33. This lower wall 33 is curved upwardly as at 34 and is welded as at 35 to the lower portion of the housing. The housing wall is cut away to form a slot 36 over which I arrange a reticulated mesh member 37. Above the mesh member I arrange a plurality of converging tooth members 38. The converging members 38 direct material towards frusto-conical ends of the rotor. From the ends the material again works towards the intermediate well portion so that the material circulates somewhat before it passes to the discharge chute 30.

The housing 22 includes a closure 39 which is complementary to the housing. The closure 39 has a flange thereon resting upon a cushion member 41 disposed on the flanges 20. Fastening members 42 serve to hold the closure member in place.

The closure 39 is provided with a filling hopper 43 which has a flaring inlet 44. The hopper 43 is in line with the well 23 so that material passing down the hopper passes into the receptacle formed by the housing 22 and closure 39.

In order to disintegrate the wadded cotton or other material being prepared, I provide a disintegrating rotor cage, indicated generally at 45. This rotor includes end members 46 which are identical in construction and consists as shown of four frame forming strips 47. To provide ample strength the strips 47 are preferably made of material of T shape and include bases 48 and upstanding ribs 49. The strips 47 are bent into quadrantal form and are preferably arranged in diametrically opposed pairs as shown in Fig. 3. The strips are welded as at 48' to the shaft 27. Within the strips I arrange reinforcing quadrantal plate members 49' which are planar and which are arranged in diametrically opposed pairs and are welded as at 50 to the shaft 27. The plate members 49' are also welded as at 51 to the bases 48 of the strips 47.

At their inner ends the strips 47 are connected to ring members 52 which are of T shape and having serrated ribs 53 forming teeth. The two ring members 52 are connected by longitudinally extending bars 54 which have outer ribs serrated as at 55 to form teeth. Thus I provide a cage which consists of the strips 47 and their connecting bars 54. Spaced axially along the bars 54 I provide quadrantal shaped circumferentially extending members 56 which include bases 57 and

ribs 58. These members 56 are welded as at 59 to the bars 54 to hold the members in circle forming position.

In the operation of my cotton picker, cotton is fed into the hopper 43 whence it passes downwardly and is engaged by the teeth on the rotor cage. The cotton is pulled apart and is carried downwardly until it passes over the screen portion 37 and into contact with the teeth 38 above the screen portion. This further tears up the wadded material. The dirt or other solid material passes through the screen 37 into the dust chamber 32 where it collects until a sliding closure 60 is removed thus opening a discharge aperture 61 through which the solid material may be removed.

In the passage of the material from the hopper to the chute, the fibres are entirely separated and freed from each other so that the contacted material is rendered light and fluffy and is adapted for reworking into mattresses and cushions.

From the foregoing description it will be apparent that I have invented a novel cotton picker which is simple to construct and which is highly efficient for its intended purpose.

Having thus described my invention, I claim:

1. A cotton picker including a housing having a well therein, a rotor cage in said housing well, said cage including a shaft, a pair of spaced end members, each end member comprising a plurality of strips arranged about the shaft and extending outwardly therefrom, each strip having its outer end secured to the shaft, the strips on the two end members being arranged in opposed pairs, a circumferentially extending ring member on the inner ends of the strips of each of the end members and secured thereto, longitudinally extending parallel bars connecting said ring members, and a plurality of circumferentially extending quadrantal members secured to said bars and arranged to form parallel spaced circles, said ring members, bars and circumferentially extending members having outwardly directed ribs, said ribs being serrated to form teeth.

2. In a cotton picker, a housing including a body having a semi-cylindrical intermediate well portion, said housing including a semi-frusto-conical well portion at each end of the semi-cylindrical well portion, said body having a closure thereon, said closure being complementary to the body, a shaft in said housing, one side of said housing at the lower portion of said well being removed to form an opening, a mesh member covering said opening, converging toothed members secured within said housing and above said mesh member,

said housing having a discharge chute extending from the body well portion, said housing having a dust chamber below the mesh member and communicating with said opening, said closure having a hopper communicating with the intermediate well portion, a rotor cage about said shaft, said cage including a pair of spaced end members, each end member comprising a plurality of radially directed, quadrantal strips having their ends secured to the shaft, a circumferentially extending ring member at the inner end of the strips of each end member and secured thereto, longitudinally extending parallel bars connecting said ring members, circumferentially extending quadrantal members secured to said bars and arranged to form parallel spaced circles, said ring members, bars and circumferentially extending members having outwardly directed teeth thereon.

3. A cotton picker including a frame, means to support the frame, spaced support members on the frame, a housing including a body having spaced flanges arranged on the support members, said body including a semi-cylindrical intermediate well portion, said housing including a semi-frusto-conical well portion at each end of the semi-cylindrical well portion, said body having a closure thereon, said closure being complementary to the body, a shaft passing through said housing, means to drive said shaft, one side of said housing at the lower portion of said well being removed to form an opening, a mesh member covering said opening, converging toothed members secured within said housing and above said mesh member, said housing having a discharge chute extending from the lower portion of the body well portion, said housing having a dust chamber below the mesh member and communicating with said opening, said closure having a hopper communicating with the intermediate well portion, a rotor cage about said shaft, said cage including a pair of spaced end members, each end member comprising a plurality of radially directed, quadrantal strips having their ends secured to the shaft, a circumferentially extending ring member at the inner end of the strips of each end member and secured thereto, longitudinally extending parallel bars connecting said ring members, and circumferentially extending quadrantal members secured to said bars and arranged to form parallel spaced circles, said ring members, bars and circumferentially extending members being disposed in the intermediate body and closure well portions and having outwardly directed ribs, said ribs being serrated to form teeth.
